CIRCUIT BREAKER

Benjamin P. Baker, Turtle Creek, Pa., assignor
to Westinghouse Electric Corporation, East
Pittsburgh, Pa., a corporation of Pennsylvania

Application February 24, 1945, Serial No. 579,615

10 Claims. (Cl. 200—82)

1

This invention relates to circuit breaker mechanisms, and more particularly to a fluid pressure operated motor designed for rapid operation of relatively heavy apparatus.

It has been proposed to provide fluid pressure responsive apparatus for actuating heavy circuit breakers which must be accelerated at rapid speeds when moved from one position to another and must at the same time be protected from violent shocks during operation. In order to render a circuit breaker apparatus of this type operative at the desired speed without being subjected to unduly heavy vibration, it is necessary to equip such apparatus with shock absorbing means. It is further desirable to provide an auxiliary means for exerting an accelerating force at least during the beginning of an operating stroke of a circuit breaker actuating motor.

One object of my invention is the provision of an improved fluid pressure motor which may be employed for actuating a heavy mechanism at high speed, and which includes improved means for arresting motion of the apparatus at the end of each stroke.

Another object of my invention is the provision of a fluid pressure motor comprising a cylinder and an operating piston and fluid pressure means conditioned by fluid under pressure supplied for actuating the piston to effect smooth deceleration of the piston as it approaches the end of an operating stroke.

It is a further object of my invention to provide a fluid pressure motor of the class just described in which the fluid pressure responsive shock absorbing means is conditioned by fluid supplied to the cylinder for exerting an initial accelerating force to the piston at the beginning of a return stroke.

Still another object of the invention is to provide an improved fluid pressure responsive operating mechanism for a circuit breaker having associated therewith a combination shock absorbing and accelerating device, including a movable abutment subject to the pressure of fluid supplied for operating the mechanism and adapted for engagement by the operating piston of the circuit breaker, and means for controlling the pressure of fluid to which the movable abutment is subjected.

The novel features that are considered characteristic of the invention are set forth in particular in the appended claims. The invention itself, both as to structure and operation together with additional objects and advantages

2

thereof, will be best understood from the following detailed description of several embodiments thereof when read in conjunction with the accompanying drawing, in which: the single figure is an elevational sectional view of a portion of a fluid pressure operated circuit breaker mechanism constructed in accordance with the invention.

Referring to the drawing, there is illustrated an operating mechanism for a circuit breaker including a cylinder casting 1 having a base portion which is adapted to be supported on a suitable insulating structure, not shown, and which is arranged to carry an arc-extinguishing structure of insulating material, not shown. The parts of the complete circuit breaker which are not shown herein are as disclosed in L. R. Ludwig et al. Patent No. 2,342,809 issued February 29, 1944, to the assignee of this invention.

10 The cylinder casting 1 is adapted to house a fluid pressure actuating means for operating the circuit breaker, the essential elements of which are shown in fragmentary form as comprising a stationary contact member 2 of tubular construction supported in the upper portion of the circuit breaker, and a movable contact element 3 adapted to be moved upwardly into telescoping engagement with the stationary contact element at one time, and downwardly and out of contact with the stationary element for interrupting the circuit at another time. For operating the movable contact element 3, there is provided a piston 4 which is slidably mounted in a bore formed in the cylinder casting 1, forming at one side thereof a piston chamber 5 communicating with an inlet passage 6, and at the opposite side of the piston a piston chamber 7 which communicates with a passage 8 by way of a port 9 formed 15 in the wall of the chamber. In the present embodiment of the invention, the piston 4 is adapted to engage a shock absorber 10 mounted at the upper end of the cylinder casting, which shock absorber may comprise a plurality of resilient rings formed of rubber or the like.

20

According to the invention, a combination pneumatic shock absorber and accelerating device, generally indicated by the reference character 12, is provided at the lower end of the cylinder casting 1 and comprises a casing section 13, which may be secured to the cylinder casting by any suitable means such as bolts, not shown, and which has formed therein a pressure chamber 14 communicating with the

lower end of the piston chamber 7 formed in the casting. The casing section 13 is provided with a centrally disposed cylinder portion 15 which is arranged coaxially of the piston chamber 7 and which has mounted therein a movable abutment or piston element 17, the upper surface of which is adapted to seat on the lower end of the wall of the piston chamber 7, as shown in the drawing. If desired, a light spring 18 may be interposed between the movable abutment 17 and the lower wall of the chamber 14 for yieldingly maintaining the abutment in the normal position as illustrated.

The pressure chamber 14 of the shock absorbing device 12 communicates with a conduit 20 leading to a conduit 21, through which fluid under pressure may be supplied both to the passage 6 and to the chamber 14 by a control valve device hereinafter described. For preventing back flow of fluid under pressure from the chamber 14 to the conduit 20, there is provided a ball check valve 22, which is held in engagement with a suitable seat formed in the casing section 13 under the pressure exerted by coil spring 23 which is interposed between the ball check valve and the lower wall of the casing section. The pressure chamber 14 also communicates with the passage 8 formed in the cylinder casting through the medium of a conduit 25 and a conduit 26 leading from the supply valve device, as hereinafter described. A ball check valve 27 is mounted within the chamber 14 for preventing backflow of fluid under pressure from that chamber to the conduit 25, the valve being urged into engagement with a suitable seat under the force of a coil spring 28. In order to limit the maximum pressure of fluid in the pressure chamber 14, there is provided a control valve element 30 which is disposed in a valve chamber 31 formed in a valve portion 32 carried by a bottom element of the casing section 13. This valve element 30 is normally held in engagement with a seat 34 under the force of a coil spring 35 mounted in the valve portion 32, and controls communication between the pressure chamber 14 and an exhaust passage 36, which is formed in an adjustable member 37 having screw-threaded engagement with the casting portion 32 for permitting regulation of the force of the spring 35.

For controlling the release of fluid under pressure from the chamber at one side of the piston 4 when fluid pressure is applied to the opposite side, there is provided a valve device generally indicated by the reference character 38, which comprises an upper casing section 39 suitably mounted on a bolting face 40 of the cylinder casting 1, and a similarly formed casing section 41 secured to a bolting face 42 of the casting. Formed in the casing section 39 is a vertically disposed bore 43 which communicates with a supply pipe 44 connected to a suitable source of supply of fluid under pressure, not shown. The bore 43 also communicates with a port 45 connected to the pipe or conduit 21, and with an atmospheric exhaust port 46.

Interposed in the supply pipe 44 is a magnet valve device 47, which may comprise a normally closed valve 47a operative upon energization of a suitable magnet coil 47b through the medium of a control circuit (not shown) to cause fluid under pressure to be supplied through pipe 44 to the bore 43.

The lower casing section 41 also has formed therein a vertically disposed bore 48 which communicates with a supply pipe 49 leading to the

same source of supply as does the pipe 44. An atmospheric exhaust port 51 and a fluid supply port 52 communicating with conduit 26 are formed in the casing section 41 in communication with the vertically disposed bore 48. It will be noted that the bores 43 and 48 are aligned coaxially. A magnet valve device 59 is interposed in the supply pipe 49 for controlling the supply of fluid under pressure to the bore 48. This device may have a construction similar to that of the magnet valve device 47, and is likewise operable upon energization of a suitable control circuit (not shown) to initiate the supply of fluid under pressure to the bore 48.

Operatively mounted in the vertically disposed bores 43 and 48 of the casing sections 39 and 41 is a valve unit having a stem 55, to the upper end of which is adjustably secured a valve portion 56 slidably mounted in the bore 43, and to the lower end of which is similarly secured a valve portion 57, which is slidably disposed in the bore 48. The stem 55 thus extends between the casing sections 39 and 41 and slides through a sleeve 61 loosely disposed between the two casing sections. One of a pair of washers 62 is interposed between each end of the sleeve 61 and the adjacent casing section for engagement with a coil spring 64 which encircles the sleeve 61 and serves to limit upward and downward movement of the stem and upper and lower valve elements 56 and 57. The stem 55 and valve elements 56 and 57 are so proportioned that upon movement of the assembly to its uppermost position, as shown in the drawing, the upper valve element 56 will cut off communication between the supply pipe 44 and the port 45 while establishing communication from the conduit 21 to the exhaust port 46. At the same time, the lower valve element 57 is positioned to close the exhaust port 51 and to establish communication from the supply pipe 49 through the port 52 to the conduit 26. It will be understood that upon supply of fluid under pressure to the upper supply pipe 44, as hereinafter explained, the valve assembly will be moved downwardly under the force of pressure applied to the upper valve element 56, until that element establishes communication between the supply pipe 44 and the port 45 and closes the exhaust port 46, while the valve element 57 cuts off communication between the pipe 49 and port 52 and connects the conduit 26 to the atmospheric exhaust port 51. It will, of course, be understood that the magnet valve devices 47 and 59 are provided for selectively controlling the supply of fluid under pressure through one or the other of the supply pipes 44 and 49, in accordance with the desired operation of the circuit breaker.

As illustrated in the drawing, the circuit breaker is disposed in its closed position with the movable contact element 3 held in telescoping engagement with the stationary contact element 2 by the piston 4, which is at the same time positioned at the upper end of the cylinder bore within the casting 1. Suitable means, not shown, may be provided for releasably locking the movable contact element 3 in this position. If it is desired to operate the circuit breaker to contact open position, fluid under pressure is supplied through the supply pipe 44 by operation of the magnet valve device 47. The pressure fluid thus supplied through the pipe 44 acts against the valve element 56 to shift downwardly the supply valve assembly so that fluid under pressure is supplied by way of the port 45, conduit 21 and passage 6 to the piston chamber 5 for shifting

the piston 4 and contact element 3 downwardly. At the same time, the valve portion 57 is carried to its lowermost position for connecting the chamber 7 below the piston 4 to the atmosphere by way of passage 8, conduit 26 and port 51. Fluid under pressure supplied to the conduit 21 also flows through the conduit 20 and past the check valve 22 to the pressure chamber 14 within the casing section 13 and exerts an upward force on the movable abutment 17.

The piston 4 is thereby moved downwardly to disengage the movable contact element 3 from the stationary contact element 2, and as it approaches the lower end of its stroke, the piston engages the movable abutment 17 and begins to move that element downwardly while closing the port 9. As hereinafter explained, the pressure area of the movable abutment 17 is greater than that of the piston 4 and thus exerts an upward force exceeding that of the fluid pressure moving the piston downwardly, but under normal conditions the piston 4 as it approaches the lower limit of its stroke will be subject to an additional force due to the inertia and kinetic energy of the moving parts, so that upon engagement of the piston 4 with the movable abutment both elements will be carried downwardly against the opposing pressure of fluid within the chamber 14 and of the light spring 18. As the piston 4 and movable abutment 17 are thus moved downwardly against the entrapped fluid within chamber 14 this fluid is further compressed and provides a cushioning force for rapidly and smoothly decelerating the moving elements, thereby arresting the opening movement of the circuit breaker without damaging impact or vibration. The maximum pressure of fluid in the chamber 14 is predetermined, in accordance with the amount of kinetic energy to be absorbed, by operation of the check valve 30, which may be set by means of the screw-threaded adjusting element 37. By starting with a fluid pressure of several atmospheres under the abutment 17 and controlling the final pressure by means of the check valve 30, the maximum kinetic energy may be absorbed with a minimum overtravel. Any tendency of the piston 4 and associated elements to rebound may be made negligible by so loading valve 30 by adjusting element 37 that the compressed fluid in chamber 14 is almost exhausted by the time the kinetic energy of the moving parts is absorbed. It will be understood that as the pressure of fluid within chamber 14 is increased, as just explained, the two check valves 22 and 27 prevent venting of fluid therefrom by way of the pipes 20 and 25.

It may be assumed that when the downward stroke of the piston 4 is terminated, the piston and movable abutment 17 will remain disposed somewhat below the position occupied by the movable abutment in the drawing, due to the weight of the associated elements. This final position may be determined by the fluid pressure in chamber 14 and the value of the spring 18.

When it is desired to effect closing operation of the circuit breaker, with the supply pipe 44 vented to the atmosphere by way of the now de-energized valve device 47, fluid under pressure is supplied through the supply pipe 49 to the bore 48 of the valve device 38 by operation of valve device 50. Pressure of fluid acting upwardly against the valve element 57 then shifts the valve assembly upwardly to vent the piston chamber 5, and to close the exhaust port 51 while causing flow of fluid under pressure through the port 52, conduit 26 and passage 8 to the port 9, which

at this time remains blocked by piston 4. At the same time, fluid under pressure flows by way of conduit 26 and conduit 25 past the check valve 27 to the pressure chamber 14, and acts upwardly against the movable abutment 17 to move that member, together with the piston 4 and movable contact element 3, upwardly with a force determined by the relatively large pressure area of the movable abutment. As the piston 4 is thus carried past the inlet port 9, the pressure of fluid supplied to the chamber 7 by way of the passage 8 becomes effective to shift the piston away from the movable abutment 17, which meanwhile is brought to rest on the lower end of the cylinder wall enclosing the chamber 7, after which upward movement of the piston 4 is continued at the rapid speed to which it has been accelerated by initial operation of the movable abutment.

From the foregoing it will be seen that a fluid pressure operated motor for a circuit breaker constructed in accordance with the invention may be associated with any type of circuit breaker mechanism involving a single pole unit, as shown in the drawing, or a multiple of such units independently operative from the single source or fluid under pressure. The circuit breaker operating mechanism comprises a cylinder and the usual piston for actuating a movable contact element, with which are associated an auxiliary movable abutment operatively aligned with the piston and a casing structure providing a pressure chamber to which fluid under pressure is supplied simultaneously with the supply of fluid for operating the piston. By the provision of suitable valves for limiting the maximum pressure to which the movable abutment can be subjected, and forming the abutment with a pressure area exceeding that of the circuit breaker operating piston, the apparatus is rendered operative to establish a desired cushioning force for arresting the movement of the operating elements of the circuit breaker at the end of an opening operation, in a safe and shock-free manner. Upon initiation of a closing operation, the relatively large movable abutment is again subjected to the pressure of fluid supplied for operating the piston in the opposite direction, and serves to accelerate the piston and the contact element of the circuit breaker, thus overcoming static friction and the inertia of the operating parts to facilitate rapid operation. It will be understood that a combination shock absorber and accelerating device having a construction similar to that already described may be installed at the upper end of a circuit breaker operating motor as well as at the lower end, if it is found desirable to provide the advantages of this mechanism for each cycle of the operation of the equipment.

While the invention has been disclosed in accordance with the provisions of the patent statutes, it is to be understood that various changes in the structural details and arrangement of parts thereof may be made without departing from some of the essential features of the invention.

65 I claim as my invention:

1. In a circuit breaker having a movable contact member, a cylinder constructed and arranged to be supplied with fluid under pressure and a piston mounted in said cylinder for actuating said contact member, fluid pressure means adapted to be engaged by said piston at least during the latter part of an operating stroke, means for conditioning said fluid pressure means with fluid under pressure for yieldingly resisting final movement of said piston as it approaches the end

of said operating stroke, and means whereby said fluid pressure means applies an initial accelerating force to said piston at the beginning of the return stroke in the opposite direction.

2. In a circuit breaker having a movable contact member, a cylinder constructed and arranged to be supplied with fluid under pressure and a piston mounted in said cylinder for actuating said contact member, and fluid pressure means conditioned by fluid under pressure supplied to said cylinder for yieldingly resisting final movement of said piston as it approaches the end of an operating stroke, said fluid pressure means applying initial accelerating force to said piston at the beginning of the return stroke in the opposite direction.

3. In a circuit breaker having a movable contact member, a cylinder constructed and arranged to be supplied with fluid under pressure and a piston mounted in said cylinder for actuating said contact member, fluid pressure means conditioned by fluid under pressure supplied to said cylinder for yieldingly resisting final movement of said piston as it approaches the end of an operating stroke, said means comprising a movable abutment having a pressure area larger than that of said piston, means for at one time subjecting said abutment to a fluid pressure opposing that for operating said piston, and means for subjecting said movable abutment at another time to a fluid pressure for augmenting the fluid pressure applied to said piston.

4. In a circuit breaker having a movable contact member, a cylinder, a piston in said cylinder for actuating the movable contact member, fluid pressure means for yieldingly resisting final movement of said piston as it approaches the end of an operating stroke, a control valve and conduit means extending therefrom for supplying fluid under pressure both to said cylinder for moving said piston and the movable contact member actuated thereby and to said fluid pressure means for building up pressure therein to resist final movement of the piston and movable contact member, and means for again applying fluid pressure to said fluid pressure means to cause said fluid pressure means to initiate movement of said piston in the opposite direction on its return stroke.

5. A fluid pressure motor comprising a main cylinder, a larger cylinder disposed coaxially of said main cylinder, an operating piston slidably mounted in said main cylinder and movable into said larger cylinder at one end of its stroke, a movable abutment mounted in said larger cylinder and engageable by said piston, means for supplying fluid under pressure to said main cylinder for moving said piston toward said movable abutment and to said larger cylinder for subjecting said movable abutment to fluid pressure opposing movement of said piston after engagement thereof with said abutment, means for limiting the pressure of fluid in said larger cylinder to a predetermined value, and means for first supplying fluid under pressure to said larger cylinder for rendering said movable abutment operative to accelerate said piston to initiate operation thereof in a return stroke and for subsequently supplying fluid under pressure to said main cylinder for continuing movement of said piston independently of said abutment.

6. A fluid pressure motor comprising a main cylinder, a larger cylinder disposed coaxially of said main cylinder, an operating piston slidably

mounted in said main cylinder and movable into said larger cylinder at one end of its stroke, a movable abutment mounted in said larger cylinder and engageable by said piston, valve means for controlling the supply of fluid under pressure to said main cylinder and to said larger cylinder at opposite sides of said piston and of said movable abutment to move said piston in a given direction and arrest its motion at the end of said stroke, and other valve means operative to further control the supply of fluid under pressure to said larger cylinder to cause said movable abutment to exert a force on said piston to initiate movement of the piston in the opposite direction to effect a return stroke.

7. In a circuit breaker, in combination, movable contact means, a main cylinder, a piston mounted in said cylinder and operatively connected to said contact means, a larger cylinder disposed coaxially of said main cylinder, a movable abutment mounted in said larger cylinder and having a pressure area greater than that of said piston, said piston being engageable with said movable abutment and movable partly into said larger cylinder, means for supplying fluid under pressure to said main cylinder at one side of said piston for operating same toward said movable abutment, means for supplying fluid under pressure to said larger cylinder for causing said movable abutment to yieldingly arrest the final movement of said piston upon engagement thereof with said abutment, means for venting said cylinder at said one side of said piston while supplying fluid under pressure to said larger cylinder for causing said movable abutment to accelerate said piston in initiating a return stroke, and means for thereafter supplying fluid under pressure to said cylinder at the other side of said piston for continuing movement thereof in the return stroke.

8. In a circuit breaker, in combination, movable contact means, a main cylinder, a piston mounted in said cylinder and operatively connected to said contact means, a larger cylinder disposed coaxially of said main cylinder, a movable abutment mounted in said larger cylinder and having a pressure area greater than that of said piston, said piston being engageable with said movable abutment and movable partly into said larger cylinder, means for supplying fluid under pressure to said main cylinder at one side of said piston for operating same toward said movable abutment, means for supplying fluid under pressure to said larger cylinder for causing said movable abutment to yieldingly arrest the final movement of said piston upon engagement thereof with said abutment, means for venting said cylinder at said one side of said piston while supplying fluid under pressure to said larger cylinder for causing said movable abutment to accelerate said piston during a return stroke, means for thereafter supplying fluid under pressure to said cylinder at the other side of said piston for continuing movement thereof in the return stroke, and adjustable means for limiting the pressure of fluid in said larger cylinder.

9. In a circuit breaker having a moving contact member, a cylinder adapted to be supplied with fluid under pressure, a piston operative within said cylinder for actuating said contact member, fluid pressure means conditioned by fluid under pressure supplied to said cylinder for yieldingly resisting final movement of said piston as it approaches the end of an operating stroke, said fluid pressure means including a movable abutment

operatively engageable with said piston for movement thereby, and means whereby said movable abutment applies an initial accelerating force to said piston at the beginning of the return stroke in the opposite direction.

10. A circuit interrupter comprising separable contact means, a main cylinder, a piston in said cylinder and operably connected to said contact means for moving said contact means to open and closed circuit positions, a second cylinder adjacent one end of said main cylinder, a movable abutment in said second cylinder, means normally biasing said abutment to a position closing said one end of said main cylinder, means for supplying fluid under pressure to said main cylinder at one side of said piston for operating said piston toward said movable abutment to actuate said contact means to open position, means for supplying fluid under pressure to said second cylinder to cause said movable abutment yieldingly to arrest the final movement of said piston upon

engagement thereof with said abutment, means for again supplying fluid under pressure to said second cylinder to cause said abutment to move said piston in a direction to initiate a return stroke for closing said contact means, and means for thereafter supplying fluid under pressure to said main cylinder at the other side of said piston to cause said piston to complete its return stroke.
